COMBINATION DISPLAY BOARD, CONTAINER, AND PAD

Samuel Weissman, New York, N. Y.

Application July 27, 1943, Serial No. 496,339

8 Claims. (Cl. 206—44)

This invention relates to a combination display board, pad and container, and more particularly to a unitary device comprising as a base a container member with a pad therein, and a display board serving as a lid for the container.

My invention has applicability in various fields including, among others, those of the jewelers and optometrists trades. In displaying articles of jewelry, the salesman generally employs a limp piece of plush or velvet which he places upon the counter and upon which the items offered for sale are deposited for the customer's inspection. When a sale is made, the jeweler is obliged to obtain wrapping tissue from some place generally remote from the specific locale at which the items are being displayed. It is one of the objectives of my invention to provide the jeweler with a unitary device containing a display board of suitable material, such as plush or the like, and a pad of wrapping tissue associated with a container removably attached to the display board. The arrangement is such that upon a raising of the display board, which serves as a lid for the container, a sheet of paper may be readily detached from the pad for wrapping the sold item. The arrangement, according to the preferred construction of my invention, thus also obviates the use of a limp display cloth, whose folds may partially obscure the displayed item or detract from its appearance, and which may constitute an unattractive background therefor. In place of such foldable cloth, the display board of my invention is made relatively rigid and flat, and thereby constitutes a more suitable display background. Furthermore, the weight of the combination of display board, pad and container maintain the device in place, and it is thus less apt to be inadvertently shifted about the counter than the conventional limp display cloth.

When used by an optometrist, my invention not only serves to display the spectacles but also enables cleansing tissue, of which the pad may be composed, to be readily removed for cleaning the lenses of the spectacles, without the necessity of reaching for lens tissue less conveniently located. And in this aspect of my invention, it is an important object to enable the lens tissue to be at all times kept free from dust, an object of which is accomplished by the use of the display board as a lid for the tissue pad container.

It is within the further contemplation of my invention to enable the container and pad to be readily and easily attached and detached from the display board, so that refills of containers

with pads may be repeatedly sold for use with the display board.

It is another object of my invention to enable the container to be formed from a die-cut and scored blank whereby, when in its fully formed condition, it will not only serve to conveniently support the pad, but will also serve to support the said display board in hinged or pivotal relation thereto. The arrangement is such that the board can be swung into its open position and, if desired, rested upon the counter or other suitable support—and, swung to its closed position flush with the top of the box for sealing the interior thereof from the atmosphere. And in this aspect of my invention, it is a further object to enable the display board to be raised and lowered into its open or closed position without any interference by the sides or other portion of the container.

20 Another important object of this invention is to enable the pad to be readily attached to the container before the container blank is folded into its fully formed condition, thereby facilitating the assembling operation.

25 Other objects, features and advantages will appear from the drawings and the description hereinafter given.

Referring to the drawings,

Figure 1 is a perspective view of the device 30 constituting my invention with the display board in its horizontal or closed position.

Figure 2 is a perspective of the device of Figure 1, shown with the display board in an open position, and showing the pad within the container.

35 Figure 3 is a section of Figure 2 taken substantially along line 3—3, showing the display board in a slightly different position.

Figure 4 is a fragmentary section of Figure 2 40 taken along line 4—4.

Figure 5 is a top view of the container portion of my invention, shown in its closed condition.

Figure 6 is a bottom view of the container of Figure 5, and

45 Figure 7 is a plan view of the flat die-cut and scored container blank, showing the pad assembled thereupon.

The device of my invention is shown in its closed operative condition in Figure 1, the plush-covered display board 10 serving as a lid for the base portion consisting of the container 11 with pad therein. In this position the cover 10 also serves as a display member upon which items of jewelry and the like can be placed to be viewed by the customer. The entire device, by virtue

of its weight, will remain wherever placed and will less likely be subject to inadvertent displacement than the conventional plush display cloth of the jeweler. As the drawing indicates, the plush cover 12 is drawn taut over the stiff foundation material 13 of the display board 10 (see Fig. 3), so that it will serve as a more satisfactory background for display than a limp cloth with folds and undulations therein.

Figure 2 shows the display board 10 in one of its open positions, the container 11 being provided with a marginal peripheral wall 14 and a recess 15 within which is placed the pad 16. It is apparent that in this condition a sheet can be readily detached from the pad, the lid closed, and the item wrapped with the said detached sheet. The entire operation is performed without making it necessary for the salesman to leave the jewelry or other items he is selling in order to obtain wrapping paper.

It will be observed that the rear marginal wall 14a has hingedly associated therewith the cover flap 17, the connection being effected along the scored edge 18. Said cover flap contains the slits 19 and 20 through which extends the tongue 21 suitably attached at its upper portion 22 to the display board 10. In the preferred form of my invention, tape 23 extends along the length of the front edge of the display board and covers the attached portion 22 of said tongue 21. A fastener 24 extends through the cover flap 17 and the tongue 21 to detachably hold the latter in place.

When the display board 10 is in the open position shown in Figure 2, it is apparent that it is in a plane intersecting that of cover flap 17. And in the position shown in Figure 3, where the display board rests upon surface 25, there is still a greater divergence between the planes of the display board 10 and the cover flap 17. This is rendered possible by virtue of the fact that the tongue 21 is of flexible material and permits various positions of the display board 10, when in its open condition.

The cover flap 17 is so proportioned that the front edge 26 and lateral edges 27 and 28 thereof are in spaced relation to the inner edges 29, 30 and 31, respectively, of the marginal wall 14. This arrangement enables the cover flap 17 to be moved to and from its closed position without contact with or interference by other portions of the container, thereby insuring a free operative movement of the display board 10. The parts are so proportioned that the said display board 10, when in its closed position, is fully supported by the marginal wall 14 constituting the top of the container 11. This arrangement will prevent a sagging or collapse of the structure under the weight of the display board 10 and the superimposed items, inasmuch as the extended surface of the marginal wall 14, rather than a mere peripheral edge, takes the load.

By reference to Figure 7 it will be seen that the blank, in its final die-cut and scored form, contains a top portion 32, a bottom portion 33, side flaps 34 and 35, a front side 36, rear flaps 37 and end flaps 38. The said top portion 32 has an inverted U shape cut-out 39 forming the cover flap 17. The bottom portion 33 contains the recess 40, the innermost edge 41 of which is disposed inwardly (Fig. 4 and Fig. 7) with respect to the edge 31 for reasons which will hereinafter appear.

The pad 16 is attached to bottom portion 33 of the container (as shown in Figures 4 and 7)

by adhesively applying a strip of tape 42 over the top edge of the pad 16 and extending said tape downwardly over edge 41 and against the outer surface of bottom portion 33 (Fig. 4). This can be done when the blank is in its unfolded condition, as shown in Figure 7. Thereafter, when the box is in its completed form, the side flap 34 will extend, according to the preferred form of my invention, to a point in proximate relation to tape 42. It is preferred that the flap 34 be so proportioned as to leave a small space or slit 43 in the base of the container, so as not to interfere with the tape 42 extending therethrough. To accomplish this, said flap 34 should be of slightly less width than the depth D of recess 40 (Fig. 7). It will also be observed that with the above-described relative positions between edge 41 of the bottom of the container and edge 31 of the top thereof, there will be no interference with the removal of any sheet from the pad. The entire pad is proportioned and disposed so as not to underlie any portions of the peripheral wall 14.

It is obvious that the entire unitary device above described is compact in form and is capable of enabling the aforesaid objectives to be obtained in a simple and inexpensive manner. It is also apparent that when an entire pad has been used up all that need be done is to operatively remove the fastener 24, and detach the entire container unit from the display board, whereupon a refill unit may be conveniently inserted.

It is understood that the embodiment above described and shown in the drawings is illustrative of my invention and not employed by way of limitation, inasmuch as numerous changes and modifications may be made within the scope of the appended claims without departing from the spirit of this invention.

I claim:

1. In a device of the class described, a display board and a base portion, the base portion comprising a container and pad therein supported by the bottom wall thereof, the upper wall of the container being apertured whereby access may be had to the pad, a cover flap pivotally associated with the container and adapted to overlie the apertured portion of the said upper wall, a flexible tongue attached to the display board and having a free portion detachably secured to said cover flap, said board being attached to the base portion only at the region of the connection of said tongue, the board being otherwise free for relative movement with respect to the flap and base portion, whereby the board may be pivotally moved between various predetermined open positions with respect to the container and a closed position in resting engagement upon the said upper wall of the container.

2. In a device of the class described, a display board and a base portion, the base portion comprising a container and pad therein supported by the bottom wall thereof, the top of the container being open whereby access may be had to the pad, a cover flap pivotally associated with the said top of the container and adapted to extend into the top opening thereof, said flap containing a slotted portion therein, a flexible tongue attached to the display board adjacent the forward edge thereof and having a free portion extending through the slotted portion of the flap, said board being attached to the base portion only at the region of the connection of said tongue, the rear edge of the board being free

for relative movement with respect to the flap and base portion, whereby the board may be pivotally moved between various predetermined open positions with respect to the container and a closed position in resting engagement upon the top of the container.

3. In a device of the class described, a display board and a base portion, the base portion comprising a container and pad therein supported by the bottom wall thereof, the top of the container being open whereby access may be had to the pad, a cover flap pivotally associated with the container and adapted to extend into the top opening thereof, a flexible tongue attached to the display board and having a free portion detachably secured to said cover flap, whereby the board may be pivotally moved between various predetermined open positions with respect to the container and a closed position in resting engagement upon the top of the container, the proportions of the board being such as to permit the rear edge thereof to extend at least to the level of the bottom of the container when the board is in a predetermined open position, whereby the board may rest upon any suitable support upon which the container is placed.

4. In a device of the class described, a display board and a base portion, the base portion comprising a container and pad therein supported by the bottom wall thereof, the top of the container having an apertured portion surrounded by a flat peripheral wall, the proportions of said apertured portion being no less than the proportions of the pad and being so disposed that no portion of the pad underlies said peripheral wall, whereby access may be had to the pad through said apertured portion, a cover flap pivotally associated with the said top of the container and adapted to extend into the said apertured portion thereof, the free edges of said flap being in spaced relation to the corresponding edges of said peripheral wall, the said display board being detachably connected to said flap, whereby it may be pivotally moved between predetermined open positions with respect to the container and a closed position in resting engagement upon the said peripheral wall.

5. In a device of the class described, a display board and a base portion, the base portion comprising a container with a plurality of walls including a bottom wall, a pad supported by the bottom wall, said bottom wall containing a slotted portion at the region of the top edge of the pad, and a flexible tape extending through said slotted portion and adhesively secured to the top edge of the pad and the outer surface of said bottom wall, the top of the container being open whereby access may be had to the pad, the said display board being movably associated with the container and supportable thereby whereby it may serve as a lid therefor.

6. In a device of the class described, a display board and a base portion, the base portion com-

prising a container with a plurality of walls including a bottom wall, a pad supported by the bottom wall, the top of the container containing a peripheral wall and an aperture surrounded thereby, the aperture being so proportioned and disposed as to expose the entire pad to view, whereby access may be had thereto, the said bottom wall of the container having a slotted portion therein at the region of the top edge 10 of the pad, and a flexible tape extending through said slotted portion and adhesively secured to the top edge of the pad and the outer surface of said bottom wall, the said display board being pivotally connected to the container and supported by the said peripheral wall.

7. In a device of the class described, a display board and a base portion, the base portion comprising a container with top, bottom, front, rear and side walls, a pad supported by the bottom wall, the top wall being apertured, whereby access may be had to the pad, the bottom wall being recessed at one end thereof, the recessed portion extending substantially to the top edge of the pad, one of said side walls being connected to the top wall and extending across the said recessed portion of the bottom wall to a predetermined point short of the said top edge of the pad, whereby a slit is formed in the region of said top edge of the pad, and a flexible tape 25 extending through said slit and adhesively secured to the top edge of the pad and the outer surface of said bottom wall, the said display board being movably associated with the container and supportable thereby whereby it may serve as a lid therefor.

8. In a device of the class described, a container adapted for detachable connection to a display board and for supporting therein a pad, the container being formed of a blank containing 40 in succession a parallel arrangement of a rear flap, a top portion, a front side, a bottom portion and another rear flap, the top portion containing a substantially U-shaped cutout portion forming a cover flap, said cover flap being 45 adapted for attachment to said display board, the bottom portion having an end portion thereof recessed a predetermined amount, whereby a pad may be placed on said bottom portion with its top edge adjacent to the innermost edge of 50 said recessed portion, the top portion being further provided with a side flap on the side thereof corresponding to the position of said recessed portion, said side flap being proportioned so as to extend across a predetermined part of said 55 recessed portion when the blank is operatively folded into its final form, the length of said side flap being less than the depth of said recessed portion, whereby a slit will be formed in the bottom of the fully formed container, for permitting fastening means for the pad to extend therethrough.

SAMUEL WEISSMAN.
